UNITED STATES PATENT OFFICE.

EDWARD NALL, OF AKRON, OHIO, ASSIGNEE TO THE GOODYEAR TIRE AND RUBBER COMPANY, OF AKRON, OHIO, A CORPORATION OF OHIO.

TENSIONING DEVICE

1,133,309.

Specification of Letters Patent. Patented Mar. 30, 1915.

Application filed May 8, 1914. Serial No. 837,205.

To all whom it may concern:

Be it known that I, EDWARD NALL, a citizen of the United States, residing at Akron, in the county of Summit and State of Ohio, have invented new and useful Improvements in Tensioning Devices, of which the following is a specification.

This invention relates to means for imposing tension on a strip of fabric and the object of the invention is to provide suitable mechanism whereby a controlled and accurately regulated tension may be imposed on a moving strip of fabric, more especially textile fabric, by setting up or causing a frictional engagement between two portions of the fabric by causing two portions of the fabric to rub together. The mechanism employed is adapted to produce a rubbing engagement between a portion of the fabric moving in one direction and a portion of the same fabric moving in an opposite direction, whereby the frictional engagement between the two produces the proper tension on the fabric.

A further object of the device is to provide means whereby the degree of frictional engagement between the rubbing surfaces of the fabric may be accurately regulated and controlled at all times, and further to provide other mechanism whereby the rubbing engagement may be instantaneously terminated to relieve the tension, said mechanism also possessing means to cause a resumption of the rubbing or frictional engagement to restore the tension as quickly.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures, Figure 1, is a view in front elevation of a device embodying this invention; and, Fig. 2, is a view in side elevation of the same device looking from the left in Fig. 1.

Mounted on a suitable support 1, are the

base portions 2 of a pair of upright housings 3 and 4 arranged opposite to one another and spaced apart. Each of the housings is provided, in the body portion thereof, with upright housings 5. The lateral edges 6 thus formed are fashioned to constitute slides. Slidably mounted in the upper portions of the upright housings 5 and adapted to shift on the slides 6 are a pair of journal boxes 7, provided with bearings 8 for the reduced ends 9 of a roll 10. Each box 7 is provided in its upper portion with a suitable socket-forming member 10 to receive the lower enlarged end of a threaded shaft 11 which is loosely received in an opening arranged vertically in each respective housing. The upper part of each housing is provided with a U-shaped horizontal slot 12 above which is a head 13. Each threaded shaft 11 is adapted to pass vertically through the slot 12 in one of the housings and mounted in the slots 12 are worm-wheels 14 which are provided with threaded apertures to run on the threaded shafts 11. Secured to the upper portions of each of the housings 3 and 4 are alined bearings 15 in which is mounted a horizontal rotatable shaft 16 arranged approximately parallel with the axis of the roll 10. This shaft bears, opposite to each of the worm-wheels, a worm 17, which is adapted to intermesh with the adjacent worm-wheel 14. The shaft 16 is further equipped with a hand wheel 18 at one end by which its rotation is secured. By rotating the shaft 16 by means of the hand-wheel 18, the worm-wheels 14 are rotated in the same direction, causing thereby a vertical, simultaneous, shifting movement of the threaded shafts 11 which raises or lowers the boxes 7 of the upper roll 10. Positioned below the journal boxes 7 in the openings 5 in the housings are journaled boxes 19 equipped with bearings for the reduced ends of a roll 20. These journal boxes 19 are vertically shiftable in the slides 6. In the lower portions of the housings are bearings for a rock-shaft 22 usually consisting simply of alined apertures. Each of the housings is furthermore provided above the bearings for the shaft 22 with curved slots 23 and 24 respectively, both of which are positioned at the lower termini of the openings 5 and with portions in open communication therewith. The balance of the slots where they project laterally be-

yond the openings 5 are formed in the arcs of circles of which the axis of the shaft 22 is the center.

Mounted on one end of the shaft 22 outside of the housing 3, is an oscillating lever 25 bearing a pin 26 which is suitably positioned to extend into and be freely movable in the slot 23, and the opposite end of the shaft 22 outside of the housing 4 is provided with a rocking arm 27 equipped with a pin 28 adapted to move in the slot 24.

It will be noted that as the slots 23 and 24 communicate with the lower portion of the openings 5 the journal boxes 19 will normally rest upon the inwardly-projecting pins 26 and 28 and be supported thereby, but if the lever 25 is shifted to the left in Fig. 2 to cause the pins 26 and 28 to move out of the lower portions of the openings 5, these pins pass from engagement with the journal boxes 19 and permit the latter and the roll 21 to shift downwardly by gravity; and of course, the shifting of the lever 25 to the position shown in Fig. 2, will instantaneously raise the lower roll to its upper operative position. The housings 3 and 4 are also equipped with a pair of alined bearings 29 adapted to support the reduced ends 30 of an idler roll 31 and on the opposite side of the housings are bearings 32 to support the reduced ends 33 of an idler roll 34.

The operation of the device is as follows: The lever 25 is shifted to the position shown in Fig. 2 and a strip of fabric 35 is extended from a suitable source of supply around the lower portion of the roller 21 and from thence to the left and partially around the roller 31, from whence it passes between the rollers 9 and 21 to and partially around the roller 34. In order to impose tension on the moving strip of fabric the wheel 18 is operated to force the upper roll 9 downwardly until the fabric passing to the left over the top of the roller 21 will be in rubbing frictional engagement with the portion of the fabric which is passing around the lower portion of the roll 9 so that the two portions of fabric engage each other and, moving as they do, in opposite directions, set up the desired rubbing or frictional engagement sought. When it is desired to instantaneously terminate the tension on the fabric for any purpose without disturbing the adjustment of the upper roll 9, the lever 25 is shifted to the left in Fig. 1, carrying the pins 26 and 28 into the curved portions of the slots 23 and 24, and out of engagement with the journal boxes 19, permitting the latter to fall by gravity, thereby shifting the roll 21 from its operative position and allowing a considerable space to exist between the rolls; this terminates frictional engagement between the two portions of the fabric. The lever 25 is usually shifted during the operation of "threading" the device

and also is used in cases of emergency where it is desired to instantly terminate tension on the fabric. It will be noted that when the lever is shifted to its upright position to shift the roll 21 to its operative position it is unnecessary to readjust the position of the upper roll to set up the desired tension.

In cases where it is desired to carry the fabric from between the friction rollers horizontally a strip of fabric is carried outwardly over the upper face of the roll 34 which constitutes a guide roll for that purpose.

I claim:—

1. A tension device for the purpose described comprising a pair of housings, an idler roll, a pair of pressure rolls mounted in the housings and positioned to permit the peripheral faces thereof to be brought into contact, one of said rolls adapted when shifted toward the other roll to press different portions of a strip of fabric passed in opposite directions and around an idler roll between them to thereby produce frictional tension on the moving strip of fabric.

2. A tension device for the purpose described comprising a pair of housings, a pair of independent rolls mounted in said housing, one of which is shiftable toward and away from the other, an idler roll, said shiftable roll adapted when moved toward the other roll to press different portions of a strip of fabric passed in different directions over the opposing faces of the two rolls and around said idler roll together, means to adjust the position of one roll, and means for holding the other roll in its inoperative position, said means when shifted adapted to move the latter roll quickly to a predetermined operative position.

3. A tension device for the purpose described comprising a pair of housings, a pair of independently-shiftable rolls mounted in said housings, an idler roll, said rolls arranged to set up a rubbing frictional engagement between different portions of a strip of fabric passing around said idler rolls and in opposite directions over the adjacent faces of said first-mentioned rolls, means embodying a threaded element adapted to control the position of one roll, an oscillating lever having connection with the other roll arranged when oscillated to shift the latter roll from an operative to an inoperative position and vice versa.

4. A tension device for the purpose described comprising a pair of housings, a pair of independently-shiftable rolls mounted in said housings, an idler roll, said rolls arranged to set up a rubbing frictional engagement between different portions of a strip of fabric passing around said idler rolls and in opposite direction over the adjacent faces of said first-mentioned rolls, means embodying a threaded element adapt-

- ed to accurately adjust the position of one roll, a rock-shaft mounted in said housings, a lever on said rock-shaft, a pin carried on said rock-shaft adapted to engage the bearing of the other roll arranged when in one position to hold said roll in its operative position, said lever when shifted permitting movement of said roller to its inoperative position.
- 10 5. A tension device for the purpose described comprising a pair of housings, a pair of independently-shiftable rolls mounted in said housings, an idler roll, said rolls arranged to set up a rubbing frictional engagement between different portions of a strip of fabric passing around said idler rolls and in opposite direction over the opposite faces of said first-mentioned rolls, means embodying a threaded element to accurately adjust the position of one roll, a rock-shaft mounted in said housings, a lever on one end of said shafts, an arm on the opposite end, said lever and arm equipped with pins, said pins adapted to constitute supports for the bearings for the other roll when in one position, said pins arranged when said lever and arm are shifted to move from engagement with said bearings to permit the movement of said roll to its inoperative position.
- 15 In testimony whereof I have hereunto set my hand in presence of two subscribing witnesses.
